UNITED STATES PATENT OFFICE.

CARL SCHÖNERT, OF NEWARK, NEW JERSEY.

BOTTLE STOPPER OR SEAL.

SPECIFICATION forming part of Letters Patent No. 731,509, dated June 23, 1903.

Application filed February 3, 1903. Serial No. 141,649. (No model.)

To all whom it may concern:

Be it known that I, CARL SCHÖNERT, a subject of the Emperor of Austria-Hungary, residing at Newark, in the county of Essex and State 5 of New Jersey, have invented certain new and useful Improvements in Bottle Stoppers or Seals; and I do hereby declare the following to be a full, clear, and exact description of the invention, such as will enable others 10 skilled in the art to which it appertains to make and use the same, reference being had to the accompanying drawings, and to numerals of reference marked thereon, which form a part of this specification.

15 This invention has reference to improvements in seals or stoppers for bottles; and the invention has for its primary object to provide a novel arrangement and construction of metal or other similar seal which is 20 adapted to be forced or sprung into the inner surface of the neck of a bottle, and preferably into an inner annular depression or recess formed in the said inner surface of the neck of the bottle, the same being usually 25 used with a piece of cork or other suitable packing material, preferably in the manner hereinafter more particularly set forth.

Other objects of the present invention are to provide a simply-constructed bottle seal or 30 stopper which can be quickly secured in position for the purpose of closing the neck of the bottle and to provide a seal of great durability and effectiveness, but which can be readily removed from the neck of the bottle 35 by means of a suitable seal-extractor or other pointed tool.

My invention therefore consists in the novel form of seal or stopper for bottles; and, furthermore, this invention consists in the various 40 novel arrangements and combinations of parts, all of which will be hereinafter more particularly described, and then finally embodied in the clauses of the claim.

The invention is clearly illustrated in the 45 accompanying drawings, in which—

Figure 1 is a side view of the neck of a bottle provided with a seal or stopper embodying the principles of the present invention, and Fig. 2 is a plan or top view of the same. Fig. 50 3 is a transverse vertical section of the neck portion of the bottle, illustrating the arrange-

ment of the inner annular depression or recess and a sectional representation of a piece of cork and the cupped metal disk or shell in position. Figs. 4 and 5 are a top view and 55 vertical section, respectively, of the form of metal disk or shell represented in said Fig. 3. Fig. 6 is a transverse vertical section of the neck of a bottle and another form of metal seal, but still embodying the principles of this 60 invention; and Figs. 7 and 8 are a top view and vertical section, respectively, of the form of metal disk or plate represented in said Fig. 6.

Similar characters of reference are employed 65 in all of the said hereinabove-described views to indicate corresponding parts.

In the said drawings the reference character 1 indicates the neck of any form and construction of bottle, and 2 is a suitably-shaped 70 annular bead surrounding the upper portion or mouth of the neck of said bottle. This annular bead 2 is made in such a manner that the upper overlapping annular portion 3 will provide an inner annular receiving depression or recess 4, as clearly illustrated in the several figures of the drawings. This annular receiving depression or recess 4 is located directly below the mouth or pouring-duct 5 of the bottle and is surrounded by annular part 80 6, preferably made inclined, as clearly illustrated. The metal shell or disk forming the seal is indicated by the reference character 7, and 8 is a piece of cork or other suitable material which is arranged between the lower 85 surface of the said seal 7 to provide a packing and a tight closure when the seal 7 is forced into its closing relation with the inner annular depression or recess 4 of the neck of the bottle in the manner to be presently described. 90

Referring now to the form of metal disk or shell represented in Figs. 1 to 5, inclusive, the shell or disk is made cup-shaped, as shown in Figs. 4 and 5, it being placed in such a position so that its marginal edge will be held 95 by the overlapping portion 3 of the bead 2 and close the mouth or pouring-duct 5 of the bottle. A piece of cork 8 or other packing material is arranged upon the annular part 6 and against the under surface of the said disk or shell, as clearly indicated in Fig. 3 of the drawings. The parts are arranged in this 100

manner within the neck of the bottle after the bottle has been filled. By means of a suitable tool acting under pressure directly upon the outer part of the said disk or shell 5 it is flattened out in the manner indicated in Fig. 3 of the drawings. The annular marginal edge 9 of the said shell or disk, following the inner contour of the annular depression or recess 4, is turned over upon the upwardly-inclining surface 6 and forced in an upward direction, as at 10, (see Fig. 3,) and thereby positively forced into a perfectly tight holding relation with the surrounding surface of the said recess or depression formed directly 15 by the upper overlapping annular portion 3 of the bottle, as will be clearly understood. At the same time the piece of cork 8 or other suitable packing material is also compressed sufficiently to provide a perfect packing, said 20 packing serving, furthermore, to prevent the liquid contents of the bottle from coming in contact with the metal surface of the seal 7.

In Figs. 6 and 8 is illustrated the reversed arrangement of the disk or shell 7, this disk 25 being indicated by the reference character 11, the main body portion of which is flat and is surrounded by a downwardly-extending bead-like marginal edge 12, which when placed in the neck of the bottle and when pressure is 30 applied thereon will have said bead-like marginal edge 12 forced into an upwardly-turned marginal bead 13 within the annular depression or recess 4, as clearly indicated in the said Fig. 6, thereby providing a perfect seal, as will 35 be clearly evident.

From the above description of my invention it will be seen that I have devised a simple device which can be cheaply made and which is readily secured in place to provide 40 a strong and effective seal or bottle-closure.

I am aware that changes may be made in the various arrangements and combinations of parts, as well as in the details of the construction thereof, without departing from the 45 scope of my invention. Hence I do not limit my invention to the exact arrangements and combinations of the parts as described in the foregoing specification and as illustrated in the accompanying drawings, nor do I confine

myself to the exact details of the construction 50 of the said parts.

Having thus described my invention, what I claim is—

1. The combination, with the neck of a bottle having an internal annular recess and an overlapping holding portion, of a disk having its marginal edge arranged in said recess and bent over therein so as to be closely doubled upon itself and tightly held by said overlapping portion, substantially as and for 60 the purposes set forth.

2. The combination, with the neck of a bottle having an internal annular recess and an overlapping holding portion, of a disk having its marginal edge arranged in said recess 65 and bent over therein so as to be closely doubled upon itself and tightly held by said overlapping portion, and a packing arranged beneath said disk, substantially as and for the purposes set forth.

3. The combination, with the neck of a bottle having a mouth 5, an annular receiving-depression 4, an overlapping portion 3, and an upwardly-inclined annular part 6, of a disk having its marginal edge arranged in said receiving-depression and turned upon said part 75 6 so as to be bent over and tightly held in said receiving-depression, substantially as and for the purposes set forth.

4. The combination, with the neck of a bottle having a mouth 5, an annular receiving-depression 4, an overlapping portion 3, and an upwardly-inclined annular part 6, of a packing arranged upon said part 6, and a disk 85 of metal upon said packing having its marginal edge arranged in said receiving-depression and turned upon said part 6 so as to be bent over and tightly held in said receiving-depression, substantially as and for the purposes set forth.

In testimony that I claim the invention set forth above I have hereunto set my hand this 31st day of January, 1903.

CARL SCHÖNERT.
